CASING FOR A LIP BRUSH AND AN EYEBROW BRUSH

Allan Costa, 682 Udall St., West Islip, N.Y. 11795

Filed Sept. 23, 1971, Ser. No. 183,287

Term of patent 7 years

Int. Cl. D3—02

U.S. Cl. D86—10 G

FIG. 1

FIG. 2

FIG. 1 is a side view of a casing for a lip brush and an eyebrow brush showing my design; and

FIG. 2 is an end view, both ends being similar.

The characteristic feature of the design resides in the particular pictorial surface ornamentation as shown, the remainder of the surface being plain and unornamented.

I claim:

The ornamental design for a casing for a lip brush and an eyebrow brush, as shown and described.
